THERMOPILE

Frank R. Higley, Cleveland Heights, Ohio, assignor to The Bryant Heater Company, Cleveland, Ohio, a corporation of Ohio

Application November 14, 1940, Serial No. 365,673

4 Claims. (Cl. 136—4)

This invention relates to improvements in thermopiles, and has reference to a novel construction of thermopile as well as to a method of making the same.

In control apparatus thermopiles are used to operate switches or valves. The current that may be set up by any one couple is of course quite small, and in order to build up a potential of sufficient amount a series of couples must be combined to give an additive result. The cost of such a thermopile as heretofore constructed has been high, and that fact has tended to limit the number of couples to whatever is found to be absolutely essential.

The present invention seeks to provide a thermopile of any required number of couples at a relatively low cost, and one in which the application of heat to the hot junctions may be accomplished easily and efficiently.

The primary object of the invention therefore is the provision of a low cost high efficiency thermopile.

Another object is the provision of a novel thermopile mounting, particularly adaptable to control mechanism for gas burners or the like.

Other objects and features of novelty will appear as I proceed with the description of those embodiments of the invention which, for the purposes of the present application, I have illustrated in the accompanying drawing, in which

Fig. 1 is an elevational view of a thermopile constructed in accordance with the invention.

Fig. 2 is an end view of the same.

Fig. 3 is an elevational view partly broken away and partly in section illustrating another embodiment of the invention.

Fig. 4 is an end view of the same partly in elevation and partly in section.

Fig. 5 is a top plan view of a further modification of the invention.

Fig. 6 is an elevational view, partly in vertical section, of the construction shown in Fig. 5.

Fig. 7 is a view similar to Fig. 6 of a slightly modified form of the invention.

Fig. 8 is a diagrammatic view illustrating one of the steps of my method of making a thermopile.

The thermopile of this invention is formed by coating a portion, preferably one-half, of each convolution of a coil of wire 10 with a metal 11 different from that of which the coil itself is formed. Various metals or alloys may be used for the wire coil, and various metals may be used for the coating on the coil. As examples of such materials I may mention a ferrous alloy as the

material for the wire coil and chromium, silver or nickel as the coating. Metals that are well separated in the series of thermoelectric power materials should be selected in order to insure a vigorous thermoelectric action. The coating may be quite thin. Both metals should be capable of withstanding high temperatures and they should have similar coefficients of expansion in order that the repeated expansions and contractions due to temperature changes may not affect adversely the adherence of the coating to the wire.

The application of the coating to the wire may be effected by plating, dipping, spraying, etc. I prefer however to plate it onto the wire. The wire after being formed into a coil of the length and diameter desired may be immersed part-way in a plating bath. Preferably one-half of the coil is immersed and this half is plated, so that after the coil is removed from the plating bath one-half of each convolution is plain wire and the other half is coated wire, and the two junctions between the coated and uncoated portions of each convolution are spaced preferably 180° apart.

When the plating, or coating by other method, has been completed and the coil has been removed from the coating apparatus, it may be permitted to remain straight, as in Figs. 1 to 4 inclusive, or it may be bent into a ring as in Figs. 5, 6 and 7. Referring first to Figs. 1 and 2, one set of junctions between the parts 10 and 11 is in this case joined mechanically but not electrically by a pair of bars 12 and 13 that are held together by high temperature cement 9, which also serves to firmly fix the convolutions in properly spaced relation and to transmit heat to the junctions. Heat is applied to one of these bars by flames 14 or other suitable means. The bars 12 and 13 are made of some non-metallic refractory material which is not a conductor of electricity, for example porcelain or oven glass.

In the form of the invention illustrated in Figs. 3 and 4 the straight coil is arranged with one set of junctions at the top and the other set at the bottom, and a tubular fluid fuel burner 15 is introduced into the coil with the burner openings in a row at the top thereof. When the burner is on the flames heat the junctions above them. Furthermore the draft created by the heat from the flames causes a flow of cool air upwardly over the lower set of junctions which helps to maintain a wide difference in temperature between the upper and lower sets of junctions. In order to accentuate this effect I may partially enclose the coil in a non-metallic refractory elec-

trical insulation material 16 providing an open-topped housing with an air passage 17 beneath the lower set of junctions, so that the air flow induced by the natural draft is confined somewhat and caused to pass over the lower junctions. Where a thermopile of this design is used in control apparatus for gas burners the tube 15 may be continued beyond one end of the coil where it may be provided with a larger orifice in order to function as the pilot of the system.

In the construction of Figs. 5 and 6 the coil after being coated in the same manner as before is bent into a hollow ring, each convolution however being separated from adjacent convolutions by an air space or other electric insulating medium. The coated portions of the convolutions in this instance are positioned at the top of the coil in order that one set of junctions may fall at the inner border of the ring and the other set at the periphery of the ring. The coil then may be associated with a pilot or other burner 18 adapted to play a flame upon all of the inner junctions.

Instead of directing a flame against the inner junctions in the ring form of the device, the inner portions of the convolutions may be sprung into an annular recess 19 in a porcelain or other heat conducting and electric insulating post 20, the inner junctions then being heated by conduction from a flame 21 which is directed against the post at a point somewhat removed from the wire coil. Care must be taken as before to maintain the inner parts of the convolutions electrically separated.

While as previously stated the coating of the wire coil may be accomplished in different ways, the procedure which I prefer at the present time is electroplating. Apparatus which may be employed in this step of the method is illustrated schematically in Fig. 8 where 22 is a tank containing electrolyte 23. 24 represents an anode of chromium, nickel, silver or other metal which it is desired to deposit upon the coil. 25 is a combination support and conductor which is caused to extend through the coil from end to end and is then rested upon opposite walls of the tank. The coil then hangs down into the electrolyte which is maintained at a level such that approximately half of the coil is immersed. 26 and 27 represent electric conductors for transmitting a current of electricity into and through the apparatus. It will be obvious that by the

operation of this apparatus the desired coating may be applied to the desired portion of the coil, generally one-half of the same.

Having thus described my invention, I claim:

- 5 1. A method of making a thermopile which comprises helically coiling a length of wire, coating one longitudinal half of said coil with a metal different from that of the wire to form two junctions of coated and uncoated wire approximately 180° apart for each convolution of the coil, bending the coil either before or after the application of the coating to form a hollow ring with corresponding junctions at the inner border of the ring and providing means for applying heat to said last named junctions, the remaining portions of the convolutions being left free and unobstructed to facilitate the rapid dissipation of heat.
- 10 2. In a thermopile, a torus comprising a helical coil of metal wire having circular hollow convolutions, a coating of a different metal on one-half of each convolution, the coated and uncoated portions of the convolutions lying upon opposite sides of a plane through the centers of the convolutions, whereby one set of junctions between coated and uncoated portions are arranged in the inner circle of the torus, and means for applying heat to said set of junctions.
- 15 3. In a thermopile, a helical coil of metal wire bent to the form of a torus, a coating of a different metal on one-half of each convolution, the coated and uncoated portions of the convolutions lying upon opposite sides of a plane through the centers of the convolutions, whereby one set of junctions between coated and uncoated portions is arranged in the inner circle of the torus, and an electric insulator and heat conductor engaging the junctions at the said inner circle of the torus.
- 20 4. In a thermopile, a torus comprising a helical coil of metal wire having circular hollow convolutions, a coating of a different metal on one-half of each convolution, the coated and uncoated portions of the convolutions lying upon opposite sides of a plane through the centers of the convolutions, whereby one set of junctions between coated and uncoated portions is arranged in the inner circle of the torus, and a heat conducting post of electrical insulation resiliently mounted in the inner circle of the torus.

FRANK R. HIGLEY.

CERTIFICATE OF CORRECTION.

Patent No. 2,310,026.

February 2, 1943.

FRANK R. HIGLEY.

It is hereby certified that error appears in the printed specification of the above numbered patent requiring correction as follows: Page 2, second column, lines 29 and 30, claim 3, for the words and comma "In a thermopile, a helical coil of metal wire bent to the form of a torus," read --In a thermopile, a torus comprising a helical coil of metal wire having circular hollow convolutions,--; and that the said Letters Patent should be read with this correction therein that the same may conform to the record of the case in the Patent Office.

Signed and sealed this 13th day of April, A. D. 1943.
